Patented Dec. 30, 1975

238,243

FLUID POWERED DISPENSING GUN OR SIMILAR ARTICLE FOR VISCOUS MATERIAL

John N. Polivka, San Diego, Calif., assignor to Owatonna Tool Company, Owatonna, Minn.

Filed July 24, 1974, Ser. No. 491,310

Term of patent 14 years

Int. Cl. D8—05

U.S. Cl. D8—14.1

FIG. 1 is a front elevational view of a fluid powered dispensing gun or similar article for viscous material showing my new design;

FIG. 2 is a top plan view;

FIG. 3 is a bottom plan view;

FIG. 4 is a front elevational view;

FIG. 5 is a rear elevational view; and

FIG. 6 is a fragmentary sectional view, taken generally along the line 6—6 in FIG. 1.

I claim:

The ornamental design for a fluid powered dispensing gun or similar article for viscous material, substantially as shown.
